UNITED STATES PATENT OFFICE.

JOHN F. OHMER, OF DAYTON, OHIO, ASSIGNOR TO OHMER FARE REGISTER COMPANY, OF ROCHESTER, NEW YORK.

SETTING AND OPERATING DEVICE FOR FARE-REGISTERS.

No. 896,315.

Specification of Letters Patent.

Patented Aug. 18, 1908.

Application filed January 14, 1907. Serial No. 352,085.

To all whom it may concern:

Be it known that I, JOHN F. OHMER, a citizen of the United States, residing at Dayton, in the county of Montgomery and State of Ohio, have invented certain new and useful Improvements in Setting and Operating Devices for Fare-Registers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention appertains to fare registers and recording machines, and comprises, first—improvements consisting in a single means for selecting the fares to be registered in either of the registers, and means for registering the fares selected for registration in either of the registers; and second—the improvements relate to means for concealing the sight opening or fare indication of the register which is not operated.

Those car lines which operate under a greater number of different values or denominations of fares than are usually employed on the average city or traction line, require a registering and recording machine of such an enlarged size, in order that it may have a capacity for taking care of such excessive number of fares, as to make its use practically prohibitive; for example, a road collecting fares running in values from 5c. fares up to and including \$1.00 fares, necessarily require a machine of such enlarged proportions as to render it inconvenient in attaching same to car. Owing to these requirements and restrictions, one of the objects of the present invention is to provide two registers and recording machines of practical and approved sizes, to take care of the fares of such lines, and a single fare selecting and operating means which are common to both registers and recorders; these machines may be located at various points of the car, and one of such machines may be employed for registering, indicating and recording fares of certain values, while the other machine is utilized for registering, indicating and recording fares of different values.

It may be further stated, that within the scope of the present invention, is contemplated the employment of two registering

and recording machines each adapted to register and record a specific single fare denomination, both of such machines being operated from a single operating device or member, the actuation of which conceals the permanent fare indicator of one machine while the other permanent fare indicator is visually exposed.

The scope of the present invention further contemplates the employment of suitable means which is actuated through the means for registering the fares, and whereby the fare exhibited at the machine previously operated, is concealed while the machine operated last exposes its fare indication.

The scope of the invention further contemplates means whereby one of the registers cannot be operated, nor can its fare be set for operation while the other machine is in a condition for operation.

The scope of the invention further contemplates means for selecting the fare to be operated, also means for operating the selected fare from different points of the car, for example, in those cars which are provided with smoking and other apartments, the fares may be selected in either machine and operated from such apartments as well as the general passenger apartment of the car.

Preceding a more detail description of the invention, reference is made to the accompanying drawings, of which—

Figure 1, is an elevation of two registering and recording machines with the fare-selecting indicators located between them; this view of the drawings also illustrates the operating devices, parts of which are removed, as well as the means for concealing the fares upon one or the other machine, while the fare is exposed on one or the other machine last operated. Fig. 1^a is a front elevation similar to Fig. 1, with the fare-selecting indicators removed; the registering and recording machines shown in this view are each designed to register and record a single class of fares; hence, the fare-selecting indicators and co-operating devices are not employed. Fig. 1^b is a modification of Fig. 1^a. Fig. 2, is an elevation of the actuating devices through which the fares selected in either of the machines shown in Fig. 1, are registered; this view of the drawings also illustrates a portion of the means for concealing the fare indicator at one register while the fare indicator of the other machine, or the last operated, is

exposed. Fig. 3, is a side elevation of one of the registers and recorders with the operating device shown in Fig. 2, appearing in section and a portion of the side of the machine cabinet broken away. Fig. 4, is a detail view of the chain connections between the selective mechanism on the exterior of the machines and that on the interior or at the rear of the machines. Fig. 5, is a horizontal sectional view of the operating device as shown in Fig. 2, with features of the actuating devices within the machines proper. Fig. 6, is a detail view of the chain connections between the fare-selective devices; this view illustrates the manner of connecting the fare-selective devices at the rear of the machines when two machines are arranged side by side, and the exterior selective mechanism shown in Figs. 1 and 4 is on one side of 10 one of said machines. Fig. 7, is a plan view of the interior of a car illustrating a register on the interior and at each end of the car; said machines being operated through a single operating member, and a single exterior fare-selective device. Fig. 8, is a detail view of the 15 connections between the exterior fare-selective devices, and exterior fare-operating devices, illustrating the manner of extending said devices to different parts of the car from which points they may be operated. Figs. 20 9 and 10, are detail views of the sprocket wheels over which the chains pass, leading from the exterior fare-selective devices to those devices from the rear of the machines. 25

Throughout the detail description, similar 30 reference characters indicate corresponding parts.

In Fig. 1, two fare registers and recorders A and B are illustrated in position similar to 35 those which they would occupy if located on the interior of one end of a car. Each of the machines registers and records different denominations of fares, for example, one of 40 said machines registers and records fares ranging from a five cent fare to a fifty-five cent fare, and the other registers and records fares ranging from a sixty cent fare up to a fare of one dollar and five and tickets and transfers in addition. The fares to be registered in each of these machines, are indicated on a dial 1 which as it is shown in Fig. 45 1 of the drawings, is arranged between the two machines; this dial contains two concentric rows of figures, the inner one of which reads from five to fifty-five and is used in connection with the register in which these fares are registered and recorded, and the outer figures on said dial are utilized in connection 50 with the fares registered in the other machine, so that a single dial is utilized in selecting the fares to be registered in either machine. When each fare is registered in either 55 of the machines, said fare is also indicated at the machine through sight openings C in the 60 usual manner.

Projected through the axis of the dial 1, is a rotatable setting rod 2 by means of which the fares are selected for each operation of either of the machines. This rod 2 extends along the interior side of the car and is rotatably supported in a suitable manner and may be grasped by the hand of the conductor and given the necessary turn to bring the pointer 3 thereon in line with the fare to be indicated upon the dial and registered within 70 the machine. It will be seen that when the pointer 3 is moved to indicate a fare shown in the outer concentric row of figures, it will extend between two of the fare indications on the inner concentric line, and when said pointer is moved to indicate a fare shown in the inner concentric line of figures, it will lie across the desired figure and extend between two of the fare indications in the outer concentric line of figures, so that there may be no 75 confusion in locating the pointer 3 or in reading the indicating dial.

On the rear side of the dial 1, there are two sprocket wheels 4 and 5 which rotate with the setting rod 2 by being fixed to said rod; these 80 sprocket wheels 4 and 5 are inclosed within a sprocket box 6 upon which the dial is mounted. The sprocket wheels are mounted in a manner to bring the teeth of one out of alignment with the teeth of the other as 85 shown in Fig. 9 of the drawings in order that different movements may be imparted to the fare-collective devices in the rear of the registers. Passing around each of these sprocket 90 wheels and running in opposite directions are two sprocket chains 7 and 8 which at their outer ends pass over pulleys 10 which are mounted upon the frame 11 of the operating mechanism in the rear of each of the register cabinets. The ends of each of these chains 95 are attached to opposite sides of a carriage 12 which is an element of the fare-selective devices.

It will be seen from the relative positions of the sprocket wheels 4 and 5, that these 100 carriages 12 will be given different movements when the selecting rod 2 is rotated, and the movement of one of said carriages will be to an inoperative position, while the movement of the other carriage will be to an 105 operative position, so that the selected fare only may be operated, and the machine in which such fare is not to be registered, in the meantime is placed in such inoperative position. The carriage 12 rides upon a horizontal 110 track 13 which is mounted on the frame 11, which as before stated, lies in the rear of each machine, and it will be readily seen that when movement is imparted to the sprocket 115 wheels 4 and 5, from the selecting rod 2, 120 these carriages will be moved upon their guide supports 13 owing to their connection with the chains 7 and 8. Supported in each of the carriages 12, is a vertically-movable 125 actuator 14 which constitutes another ele- 130

ment of the fare-selective devices. This actuator, when the carriage 12 moves it to an operative position, is moved upwardly in its guiding support 12 by the transverse lifting bar 15 which moves on end guides 16 attached to the frame 11; this movement of the actuator 14 is accomplished from the lifting bar 15 through a lug 17 which projects from a side of the actuator into a horizontal slot 18 in the lifting bar, said slot extending the length of said lifting bar in order that the carriage with the actuator may be moved to any desired position to be placed in operative relation with the fare to be registered in the machine.

Projecting from the rear side of each of the actuators 14 is a lug 19 which, when either actuator is moved in an operative position on the carriage 12, lies between any two of 20 the locking bars 18 as shown in Fig. 5; these locking bars 18 are secured to the side or inner face of the frame 11, and their purpose is to serve as a lock to prevent the operation of each actuator when the latter is moved to a 25 position below one of said bars 18 as is shown in Fig. 4 to the left, and also to guide the lug 19 when in an operative position, thereby locking the setting device and preventing movement thereof until the selected fare has 30 been registered and the actuator returned to normal position. To the right in this figure, the lug 19 is shown in a position between two of the bars 18 and in which position said actuator may be elevated by the lifting bar 15.

It will be understood that in selecting a fare to be registered in one or the other of the machines, the setting rod 2 is rotated to bring the pointer 3 to the desired position to indicate the fare to be registered; this movement of said rod correspondingly moves the carriages 12 as shown in Fig. 4, one of said carriages being moved to an operative position in the rear of the register or machine to be operated; for example, as shown to the 45 right in Fig. 4, and the other carriage being moved to an inoperative position in the rear of the register or machine which is not to be operated; this inoperative position is shown to the left in Fig. 4, where the projection 50 19 lies below one of the locking ribs or bars 18. It will be understood that this common movement by which one of said actuators 14 is moved to a position between the bars 18, and the other actuator is simultaneously

55 moved in alinement with one of the bars 18, is accomplished by mounting the sprocket wheels 4 and 5 with the teeth of one wheel out of alinement with those of the other wheel and as shown in Fig. 9. The carriage 60 which is so moved to an operative position and as shown in Figs. 2 and 4, is maintained in such position by a temporary locking roller 20 which rides recesses 21 in a track 22 fixed to a side of the carriage track 13. 65 The locking roller 20 is on the end of a pin 23

which is mounted in the carriage frame and said roller is normally held down by a spiral spring 24 placed upon the pin. The actuator 14 which is moved to an operative position is elevated to register the selected fare in one or the other of the machines through an elevation of the lifting bar 15, the latter being actuated from a bell crank lever 25 which is connected to an operating member 26, which in turn, is connected to 70 an operating member 27 which extends into the car at suitable points to be operated to register each fare after the selection of such fare. The connection between the operating members 26 and 27 is in the form of a lever 80 28 which is fulcrumed on a bracket 29 extending from a convenient part of the car, and one arm of which connects with the member 26 and the other arm of which connects with the operating member 27. 85

In the event it is desired to extend the operating member 27 in opposite directions, this may be done as shown in Fig. 8, where 30 designates the interior wall of a car which partitions said car into two compartments, 90 one a smoking compartment and the other a general passenger compartment. In order to enable the conductor to select and register fares from either of these parts of the car, the selecting rod 2 is passed through the partition or wall 30 and an operating member 27 is likewise passed through such partition, and on each side of said partition, there is a dial 1 such as is shown in Fig. 1, and the selecting rod 2 is provided with two pointers 3. 95

In the use of two machines, either in proximity to each other as shown in Fig. 1, or more widely separated as shown in Fig. 7, it is essential that the sight opening in the machine last operated be closed, or that the fare last indicated in such machine be concealed when the next succeeding operation of the other machine takes place; this is necessary as a means of directing the attention to the indication of each fare to the machine in which such fare is registered. This result is accomplished by means of an arm 31 which is pivoted mid-way of its length and carries on each extreme end a depending 105 arm 32 which supports a blind 33 which is adapted to move in and out of a position to conceal the sight openings C—C in either machine. When the blind is moved over the fare sight opening in one machine it is 110 elevated above such opening in the other machine, and this movement is accomplished in each operation of one or the other register as follows: Depending from each end of the pivotal arm 31 is a rod 36 which extends down through a guide 34 in the frame 11 and is in a position to engage the ledge 35 which projects from a side of the lifting bar 15—see Figs. 2 and 5. It will be seen that when the lifting bar 15 of either machine is 115 120 125 130

elevated, the depending rod 36 will be engaged and the lever 31 will be tilted to elevate the blind 33 from the sight opening in the register operated, and the corresponding blind 33 will be lowered over the sight opening in the other machine.

I do not wish to limit myself to the particular means herein shown and described for thus concealing the fare indication at one machine while exposing it at the other, as it is clear this may be done in a manner different from that shown and described herein; neither do I wish to limit myself to the application of the means to expose and disclose the fare indications only, as the same means may be employed to expose and disclose other features in the register, such as the trip or total passenger wheels, the direction indicator, etc. I therefore, claim broadly means for use in connection with two fare registering machines whereby the fare indication and other exposed matter at one machine will be concealed simultaneously with the revealing of the fare indication at the other machine.

Referring to Fig. 1^a of the drawings, the machines shown therein are each adapted to register a single fare, such for example, as cash fares in one machine, and transfers or tickets in the other machine. In such use of two registering machines, the fare-selective mechanism shown in Figs. 1 and 4 would be dispensed with as is obvious, and the fare indications at each machine would be permanent, but the use and operation of the blinds 33 would be similar to their use and operation as shown and described in connection with Fig. 1.

Fig. 1^b is a detailed view of the front elevation of Fig. 1^a, and which shows the blind enlarged sufficiently to conceal the total trip or passenger wheels, and also the direction indicator and the fare indication. It will be observed that the trip or passenger wheels and also the direction indicator are observed through apertures in the blind.

Single fare registers are sometimes used without permanent fare indications, and the purpose of this invention would be subserved by adapting the blind to expose the total wheels only, or the direction indication only, and to simultaneously disclose those features on the other machine. If it is desirable to expose the total wheels only, or the direction indication only, or both the total wheels and the direction indicator, the blind will be arranged accordingly.

Referring to Fig. 6, the arrangement and connection of the fare-selective devices there shown are adopted in cases where it is necessary to locate the two machines side by side; in this case a single sprocket chain 8 is employed and the two carriages 12 are connected to said chain at suitable points to enable them to be moved the proper extent in

the rear of their respective machines or registers. In this application of my improvement, a single setting rod is employed and also the dial 1 as shown in Fig. 1, but it is only necessary to employ a single sprocket 70 wheel 4 or 5 to drive the chain 8, and these several elements, to-wit—the rod 2, the dial 1 and the sprocket wheel may be located on one side of one of the registers instead of between the two registers as shown in Fig. 1. 75 The carriages are so connected to the chain that only one of said carriages at a time may be moved to operative positions or in line with the space between any two of the locking bars or ribs 18.

Referring to Fig. 7, this illustrates a top view of a car in which two registers are located one at each end, and both of said registers being operated by the same means hereinbefore described and the fare selected 85 in one or the other by the same means; for example, the setting rod 2 extends the length of the car, and at each end thereof is arranged the fare-indicating dial 1 with the necessary connections as shown in Fig. 4, with a single 90 sprocket wheel 4 or 5 fixed to each end of said rod and the necessary chain connections between said sprocket wheels and the respective carriages 12. An operating member 26 is likewise similarly connected to each of the 95 lifting bars 15 in the rear of the machines.

So far as I am aware, I am the first to employ a plural number of fare-registering and recording machines in a car with means for selecting the fare to be registered in one or 100 the other of such machines, said means being common to both machines, and further, means for locking the machine in which a fare is not collected for operation, and further, means for concealing the fare and other 105 data exposed at the last machine operated concurrently with the exposing of the fare at the machine next operated, I therefore, claim broadly these features; said last means being applicable to any type of register or 110 any type of register or recorder combined.

I claim:

1. The combination with two fare registering and recording machines, and a separate casing inclosing each machine, of a single selective mechanism whereby the fare to be registered in either machine is selected, and means for actuating the mechanism of the selected fare in each machine.

2. The combination with two fare registering and recording machines, and a separate casing inclosing each machine, of an actuating device for each machine, and selective means common to both registers or machines and whereby the fare to be registered in one 125 or the other of said machines is selected.

3. Two fare registering and recording machines, a separate casing inclosing each machine, and actuating devices for each register, of selective mechanism adapted to be 130

placed in operative relation with a fare to be registered in either machine, and a setting rod and a dial common to both of said machines and through which the fare is selected and indicated for one or the other of said machines.

4. Two fare registering and recording machines, a separate casing inclosing each machine, and an actuating device for each register, of a selective device for each register adapted to be placed in operative relation with the actuating device of each register and the selected fare to be registered in each register, a fare-selecting rod and indicator common to the devices of both registers, and connections between said rod and the devices of each register whereby one of the registers is placed in an inoperative position while the fare is set in the other for operation.

5. Two fare registers adapted to register different classes of fares, a separate casing inclosing the mechanism of each register, of means for simultaneously concealing the fare last registered in one machine and exposing the indication of the fare to be next registered in the other machine.

6. In a fare register, the combination with two fare registers adapted to register different classes of fares, and means for simultaneously concealing the fare last registered in one machine and exposing that registered in the next succeeding registration in the other machine, said means for so exposing simultaneously, one fare and concealing the other, being actuated during the operation of registering each fare.

7. The combination with a plurality of fare registering and recording machines, each one of said machines being designed to register different classes of fares, a single selective member by which a fare to be registered in either of said machines is placed in an operative position, an actuating member or device for each of said registers and through which the collected fare may be registered, a dial common to both of said registers and upon which the fare selected in either register is indicated in the operation of selecting the fare to be registered.

8. The combination with a plurality of fare registering and recording machines, each one of said machines being designed to register different classes of fares, a single selective member by which a fare to be registered in either of said machines is placed in an operative position, an actuating device for each of said registers and through which the collected fare may be registered, a dial common to both of said registers and upon which the fare selected in either register is indicated in the operation of selecting the fare to be registered, and means for simultaneously concealing the fare indicated at one register and exposing the fare at the other register.

9. Two fare registering and recording ma-

chines, each of which is confined to registrations and indications of certain fares, separate casings inclosing said machines, and operating devices to register the fares in said machines, of means working in unison and adapted to conceal the fare indication at one machine and to expose it at the other machine.

10. Two fare registering and recording machines, each of which is confined to the registration and indication of certain specific fares, a separate inclosing case for each machine, and operating devices for each machine, of means actuated by the operating devices of one or the other machine for concealing the fare indication at one machine and exposing it at the other machine.

11. Two fare registering and recording machines, each of which is confined to the registration and indication of certain specific fares, a separate casing inclosing the mechanism of each machine, operating devices for each machine, and common means for actuating the operating devices of both machines, of means actuated by said operating devices simultaneously with the registration of fares in either machine and whereby the fare indication is simultaneously concealed at one machine and exposed at the other.

12. Two fare registering and recording machines, inclosed in separate casings, each of which is confined to the registration and indication of a selected fare, operating devices for each machine, common means for actuating the devices of both machines, and means actuated by said operating devices simultaneously with the registration of fares in either machine and whereby the fare indication is simultaneously concealed at one machine and exposed at the other.

13. A plurality of fare registering and recording machines, one of which is adapted to register fares of different values from those of the other, fare selecting devices simultaneously movable into a position to operate a selected fare in one machine, and out of an operative position with the other machine, an exterior rotatable member, intervening connections between the fare selecting devices of both machines and said rotatable member, whereby the fare selecting devices of one machine are moved into operative relation with a selected fare, and the fare selecting devices of the other machine are moved out of an operative relation with any fare.

14. Two fare registering and recording machines, one of which is adapted to register fares of different values from those registrable in the other machine, fare operating devices simultaneously movable into a position to operate a selected fare in one machine, and out of an operative position with any fare not selected in the other machine, a fare-setting member, intervening connections between the fare-operating devices of both

machines and said fare-setting member, whereby the fare-operating devices of one machine are moved into operative relation with the mechanism of a selected fare in one machine, and the fare-operating devices in the other machine are moved out of an operative relation with the mechanism of any fare registrable therein, and an indicator showing the fares registrable in both machines.

15. Two fare registering and recording machines inclosed in separate casings, and each of which is confined to registrations and indications of a specific denomination of fare, operating devices for each machine adapted to register the fares thereof, a permanent indicator for each machine, means adapted to concurrently conceal the fare indicated at one machine and to expose the fare indicated 20 at the other machine, said means being actuated by the operating devices of either machine.

16. Two fare registering and recording machines inclosed in separate casings, each 25 confined to a specific class of fares, a permanent indicator for each machine to exhibit the fares thereof, operating devices for each machine through which the fares of each machines are operated, means adapted to conceal the fare indication of one machine and to expose that of the other machine simultaneously, said means being operated in one direction by the operating devices of one machine, and in an opposite direction by the operating devices of the other machine.

30 17. Two fare registering and recording machines, each of which is confined to a specific fare, a permanent indicator to exhibit the fares registered in each machine, operating devices for registering the fares in each machine, and means adapted to conceal the fare indication of one machine and to expose that of the other machine simultaneously.

35 18. Two fare registering and recording machines, each of which is confined to the registration and indication of certain fares, a permanent indicator at each machine to indicate the fares registered at each machine, a total indicator at each machine to indicate the total fares registered in each machine, operating devices adapted to register the fares of each machine, and means for concealing the permanent fare indicator at one machine and to expose it at the other machine simultaneously with one operation of one or the other machine.

40 19. Two fare registering and recording machines inclosed in separate casings and each of which is confined to the registration and indication of a specific class of fares, a permanent indicator at each machine to indicate such fares, a total indicator at each machine to indicate the totals of each fare, a direction indicator at each machine to indicate the direction of the travel of the car, operat-

45 ing devices adapted to actuate the total fare indicator with each operation of registering a fare in one or the other of the machines, and means for concealing the permanent fare indicator at one machine and exposing it at the other machine simultaneously with the registration of a fare in either machine.

50 20. The combination with two registers, and a separate inclosing case for each of said registers, of a single selective mechanism whereby the fare denomination to be registered in either machine is selected, and means for actuating the mechanism of the fare selected for registration in either machine.

55 21. The combination with two registers, and a separate inclosing case for each register, of an actuating device for each register, and selective means common to both registers, and whereby the fare denomination to be registered in one or the other of such registers is selected.

60 22. Two registers each of which is confined to the registration and indication of certain denominations of fares, a separate inclosing case for each register, and operating devices for each register, of means working in unison and adapted to conceal the fare previously indicated at one register and to expose the fare indication at the other register.

65 23. Two registers inclosed in separate casings and each of which is confined to the registration and indication of certain denominations of fares, operating devices for each register, and means working in unison and adapted to conceal the fare indicated at one register and to expose it at the other register.

70 24. Two registers, a total indicator at each register to indicate the total fares registered in each machine, operating devices adapted to move the total indicator, and means adapted to conceal the total indicator at one machine and to expose it at the other machine, said last-named means being operated simultaneously with the operating devices through which the total indicator of either machine is operated.

75 25. Two fare registers each of which is confined to the registration of certain fares, a direction indicator for each register, and means adapted to conceal the direction indicator at one machine and expose it at the other.

80 26. Two fare registers each of which is confined to the registration of certain fares, operating devices for each machine, a total indicator, a direction indicator, and means adapted to conceal the total indicator and the direction indicator at one machine and expose them at the other.

85 27. Two fare registers, each of which is confined to the registration of specific classes of fares, and operating devices for each machine adapted to actuate the registering mechanisms of such fares, of visible indications of the fares at both machines, and means adapted to conceal the visible indica-

tion at one machine and to expose it at the other machine, said last-named means being operated by either of the operating devices of the two machines.

5 28. Two fare registers, each of which is confined to the registration of a specific fare, a separate inclosing case for each register, operating devices adapted to register the fares of each register, an arm supported between the registers, a depending member at each end of the arm and arranged to be operated by said operating devices, and means carried on said arm for simultaneously concealing the fare indicated at one register and exposing that at the other register.

10 29. The combination with two registers, a separate casing inclosing each register, of a single selective mechanism common to both registers and by means of which the fares to be registered in either machine may be selected, and means for actuating the mechanism of the fare selected in either machine.

15 30. In a fare register, the combination with two registering machines, an inclosing case for each machine, means for registering and indicating the fares of each machine, of a single fare-selective mechanism common to both machines, indicators bearing indications corresponding with the indications at the machine, and operating means adapted to register and indicate the fare selected in either machine.

20 31. The combination with two fare registers, a separate inclosing case for each machine, a single selective mechanism extending to distant points from where the fare to be registered in either machine may be selected, a plurality of fare indicators located at different points, means actuated by the movement of the single-selective mechanism to indicate the same fare on each of said fare indicators, and to correspond with the fare indication of one or the other register after the operation of such register.

25 32. The combination of a register, selective mechanism by means of which the mechanism of the fare to be registered is selected, and means for actuating the mechanism of a selected fare to register the same, said means comprising a multiple arm lever, a connec-

tion between one arm of said lever and the register mechanism, and extended connections from the other arms of said lever and through which said lever is actuated.

33. The combination with a car having different compartments, of two registers placed therein in separate casings, a separate actuating mechanism for each register extending into the different compartments, and a selective mechanism common to both of the register mechanisms and by means of which the fare to be registered in either machine is selected, said selective mechanism extending into the several compartments of the car.

34. Two fare registers inclosed in separate casings and each of which is confined to register a specific fare, operating devices adapted to register such fares, an arm supported between the registers, a depending member on each end of said arm and arranged to be operated upon by the operating devices, and means carried on said arm for concurrently concealing the fare indicated at one register and exposing that at the other register.

35. Two registers each of which is confined to register a specific denomination of fare, visible indications at both registers, an arm supported between the registers, said arm having extensions loosely connected to the case of the registers, curtains connected to said extensions to conceal the visible indication at one register and expose it at the other.

30 36. Two fare registering and recording machines, each of which is confined to the registration and indication of different specific fares, a casing inclosing each machine, a permanent indicator common to both machines and adapted to indicate the fares registered in each machine, and operating devices for each machine, of means adapted to conceal the fare indicator of one machine and expose that of the other machine simultaneously with the operation of registering a fare in one or the other machine.

40 In testimony whereof I affix my signature, in presence of two witnesses.

JOHN F. OHMER.
